ELEVATOR SIGNAL SYSTEM

Filed Dec. 14, 1928

FIG. 1

INVENTOR.

CARROLL E. ORR.

BY
Martin J. Finnegan
ATTORNEY.

UNITED STATES PATENT OFFICE

CARROLL E. ORR, OF ORANGE, NEW JERSEY, ASSIGNOR TO ELEVATORS SUPPLIES COMPANY, INC., OF HOBOKEN, NEW JERSEY, A CORPORATION OF NEW JERSEY

ELEVATOR SIGNAL SYSTEM

Application filed December 14, 1928. Serial No. 326,062.

This invention relates to elevators and particularly to signaling means whereby persons desiring to make use of any one of a group of elevators may register a call for the nearest elevator and receive in return a signal upon its approach.

The invention in certain of its phases consists in certain improvements and additional features of novelty to the system disclosed in the Smalley & Reiners Patent #826,752 and in the application for United States Letters Patent filed by William F. Beatty on October 31, 1925, bearing Serial #65,919.

One of the objects of the invention is to provide means operative as an incident to the stopping of an elevator at any floor to produce a signal for that floor independently of the usual signal registering means, and to cause such a result to be effected without the possibility of interruption in the energization of such signal already produced through the instrumentality of the said usual signal registering means.

With these and other objects in view the invention will be described in its preferred embodiment with respect to the accompanying drawing, which may aid in the understanding thereof.

In the drawing, which is a schematic illustration of the electrical circuits and parts involved when the invention is applied to a plurality of elevators serving a plurality of floors, reference characters A and B designate respectively two elevators of a group of any desired number serving any desired number of floors, three of which are indicated by the numerals V, VI and VII, the floor lanterns for such floors being indicated by the reference characters 5AU, 5AD, 6AU, 6AD, 7AU, 7AD, 5BU, 5BD, 6BU, 6BD and 7BU and 7BD. Signal sending devices in the form of the usual push buttons are indicated at 5U, 5D, 6U, 6D, 7U and 7D. The customary signaling devices for the benefit of the operator of the elevators are indicated at AL and BL respectively. The means for causing the operation of the stop signals both within and without the elevator at a predetermined time in response to the operation of the push buttons may take any well-known form, but as illustrated herewith comprise the usual commutator mechanism involving a plurality of brushes traveling over associated segments and strips in synchronism with the travel of the associated elevators but at a proportionately reduced speed; the various brushes, strips and segments involved in the downward travel of elevator A being indicated by reference characters 45, 46, 58, 73, 24, 55, 56, 57, 70 and 74 respectively and those involved in the downward travel of car B being indicated by a similar showing at the right of the drawing.

In the circuits of the "up" push buttons and stop signals are the signal operating and reset magnets, the "down" magnet groups for the three floors illustrated being designated collectively by the reference character M. In the cars A and B are the usual transfer and cutout switches operated by the buttons 10 and 11 respectively. However, it will be seen as the description progresses that these transfer and cutout switches which are normally closed need not be considered as a part of the present invention—at least in its normal operation. They are preferably used to provide means for simultaneously transferring waiting passenger signals to the other cars and at the same time obliterating all the advance signals for the car whose switch is thus operated. The principal novel phases of the invention will now be described. Reference character 12 indicates an electromagnet or relay adapted to be energized at all times while the elevator hoisting motor for car A is in operation. This may be accomplished by the use of any of the devices illustrated for a similar purpose in the drawings of the Andren Patent No. 1,109,950, or any equivalent thereof which is of common knowledge capable of substitution therefor; for the purposes of the present disclosure the electro-magnet 12 may be considered as connected by means of the wires 13 and 14 with full voltage terminal points on the elevator control board (not shown). In practice coil 12 may even be the well-known brake releasing coil usually supplied in connection with the hoisting motor brake and adapted to be

55

60

65

70

100

energized to release the brake upon starting the hoisting motor.

Coil 12 preferably has associated therewith contacts adapted to be bridged by the armature 15 when the latter is attracted by the energization of the said coil. 16 designates a resistance unit which may be inserted in the circuit passing through the electro-magnetic relay 17, which circuit is shown tapped from the high voltage leads designated by the characters "H. V." With this arrangement it is apparent that the relay 17 will be energized at all times while the contacts at 15 are bridged—in other words at all times while the car A is in motion.

Associated with the relay 17 is an armature 18 normally resting on the two contact members 19 and 20 but adapted to be lifted therefrom whenever the relay 17 is energized. These contact members 19 and 20 form part of one branch of a circuit leading from the high voltage leads to the current conducting strip 24 on the commutator of car A, the purpose for which will presently appear.

Associated with the relay 22 is the armature 26 adapted to bridge the contacts 27 and 28 and to be lifted therefrom upon energization of the relay 22. These contact members 27 and 28 control a circuit to the relay 30 which in turn has associated therewith an armature 31 adapted to rest upon the contacts 32 and 33 upon the de-energization of the said relay 30. Resistances for the circuits just described are indicated at 34, 35 and 36. Relay mechanism for car B similar to that just described with reference to car A is indicated by the reference characters 40, 41, 42 and 43 in the drawing, it being understood that every car of the system is provided with similar mechanism for the purpose now to be described.

To explain the purpose and the functioning of the system a typical operation will be followed through. Let it be supposed that car A is descending and push button 6D has been pressed by a person waiting at the sixth floor. Let it further be supposed that segment 45 represents the sixth floor "pick-up" segment on the "down" side of the commutator for car A and segment 46 the sixth floor "reset" segment for the "down" direction of travel. The operation of the push button 6D will close a circuit to the magnet 6M passing from the battery 47 through the said magnet and the switch operated by the button 6D.

The energization of magnet 6M which is thus produced causes finger 49 to make contact with the mercury cup 50 so as to permit a circuit to be closed from the negative side of the high voltage source of current through conductor 51, cup 50 and finger 49, conductor 52 and 53, current conducting segment 45, thence through one of the pairs of spanning brushes indicated at 55, 56 and 57

to the segment 58 and thence by conductor 59 to the lantern 6AD, thence back to the positive feed by way of conductor 62, normally closed cutout switch 63 and conductor 64. This circuit is first closed, it will be understood, by the leading pair of brushes 55 of the commutator for car A, the closure taking place upon the arrival of car A (which is assumed to be the nearest car traveling downwardly) within the predetermined distance of the sixth floor. In this respect the operation is similar to that preferred in the art whenever the system disclosed in the aforesaid Smalley & Reiners patent is used. Furthermore, as is usual in the aforesaid Smalley & Reiners system, the signal AL of car A is energized upon the approach of the elevator to a point within the predetermined zone of the sixth floor through the instrumentality of the bridging member 65 and the current conducting strip 66, these operating to close a circuit to the aforesaid signal AL in parallel with the circuit traced through the segment 58 and lantern 6AD.

During normal operation, that is to say while a car is traveling in either direction, its relay units corresponding to those indicated at 12, 17, 22 and 30 with reference to car A will remain in the condition in which these units appear in the drawing. Thus whenever car A is in motion the bridging members 15 and 26 are in circuit-closing position while the bridging members 18 and 31 are in circuit-opening position, as shown. Therefore in the event that car A passes the sixth floor without stopping to pick up the person waiting at that floor who had previously registered a signal through the instrumentality of button 6D, the signal thus registered will remain potentially operable by the next approaching car (car B in the present instance) inasmuch as the circuit to the restoring magnet 6R will remain open at the contacts 32 and 33 notwithstanding its closure at another point by the operation of the traveling bridging member 70 at the moment of passing the sixth floor.

Such automatic transfer of the stop signal initiated by the pressing of button 6D will continue until a car stops to answer the call, it being understood that all commutators are cross-connected in a manner similar to the cross-connections indicated for the commutators of cars A and B. As soon as another car stops at the sixth floor its bridging member corresponding to the member 31 shown with reference to car A will cause a closure of the restoring circuit in conjunction with the operation of the associated commutator, thereby restoring the mercury finger 49 to its normally raised position. Such closure is brought about by the electrical interconnection of the relay units of each group in such a way that the stopping of the associated elevator—whether or not a signal for a stop has

been previously registered—causes each of the units of the relay group to reverse its position. Thus, for example, after car A stops at the fifth floor to let a passenger off, and even though no signal has been registered by the signal sending means for the fifth floor, the immediate result, occurring as an incident to or a condition precedent to such stopping, (dependent upon the particular form of mechanical equivalent employed in place of the relay 12) will be the de-energization of the relay 17 and the consequent bridging of the contact members 19 and 20 by the armature 18. Such bridging of the contacts 19 and 20 operates to immediately close a circuit to the floor lantern 5AD in shunt with the circuit (which may or may not have been previously closed on such occasion) through the "pick-up" segment 73 and including the current conducting strip 24, the circuit being traceable as follows: from the positive side of the high voltage source through conductor 64, normally closed cutout switch 63, conductor 62, lantern 5AD, conductor 72, segment 73, thence across the bridging member 74 to strip 24, thence by way of conductor 75 and contact members 19 and 20 to the negative side of the high voltage source of current.

The result is the operation of the floor lantern 5AD to announce the stopping of the car A at the fifth floor to any persons at that floor who may not have registered a signal but nevertheless may desire the use of the elevator. In this respect the result is similar to that obtained by the use of the instrumentalities disclosed and claimed in the aforesaid Beatty application Serial No. 65,919; but the present invention improved upon the Beatty arrangement by causing the restoration of the signal sending mechanism to inoperative condition to depend upon the prior completion of the shunt circuit to the floor lantern passing through the strip 24—this being the circuit just traced. Making the restoration so dependent upon the prior completion of this shunt circuit eliminates all danger of a temporary extinguishment of the floor lantern between the restoration to open condition of the normal lantern circuit passing through the "pick-up" segments of the commutator—which restoration takes place upon the arrival of the restoring brush 70 on the corresponding reset segment—and the closure of the shunt circuit through the strip 24. Such temporary obliteration of the signal at the floor will inevitably occur frequently, thereby causing an appearance of defective circuits and a flickering action on the part of the floor lantern, unless means are provided for making impossible any cancellation of the normal signal sending circuit until completion of the auxiliary shunt circuit through the strip 24. The manner in which this is accomplished by the invention disclosed herewith is as follows.

Inasmuch as the relay 22 depends for its energization on the closure of a circuit passing through the contact members 19 and 20, this relay 22 is not energized until the bridging of the said contacts by the armature 18. Now, since the floor lantern 5AD is immediately included in circuit with the contacts 19 and 20 when they are bridged by the armature 18, it is apparent that the relay 22 and the lantern 5AD are in parallel circuits which are simultaneously closed. Consequently it is positively established that the lantern 5AD will be energized by means of this parallel circuit through the strip 24 with the first energization of the relay 22, and certainly before the relay 22 has exerted its full magnetic effect upon the armature 26 to withdraw it from the members 27 and 28 on which it normally rests.

Now until the armature 26 is thus withdrawn from the contacts 27 and 28 the relay 30 remains energized and hence the circuit to the restoring magnet 6R remains open at the contacts 32 and 33; this circuit being closed only by the dropping of the armature 31 pursuant to the de-energization of the relay 30, which in turn is brought about after the raising of the armature 26 previously described. It is therefore apparent that no energization of the restoring magnet 6R can occur until after the energization of the floor lantern 5AD. The same sequence of operation occurs for each floor at which an elevator is stopped through the operation of the corresponding means for the other floors and other elevators. All possibility of flickering of the floor lanterns or temporary extinguishment thereof between the restoration of the normal push button controlled signal sending circuits and the establishment of the shunt circuits (which are independent of the push button) is therefore eliminated.

The above specification and the annexed drawings are to be considered only as illustrative of what I deem the preferred embodiment at this time. The invention is not limited to this specific form or to any particular combination or application of the parts, but embraces all modified forms and constructions within the scope of the appended claims. Furthermore, the ready adaptability of this invention to systems differing from the aforesaid Smalley & Reiners system (such as the system of the Bassett Patent No. 1,666,589 for example) will be apparent to those skilled in the art.

I claim:

1. In an elevator signaling system, a plurality of cars each serving a plurality of floors, individual landing signals at each floor for each car for indicating the direction of movement of said cars, controlling means including passenger controlled means at each floor common to all cars for preparing said

signals for energization, car controlled means individual to said cars and operable by and in accordance with movements of the associated car and cooperating with an operated passenger controlled means for energizing the signal for said car upon approach of said car to the signaled floor, means cooperating with said car controlled means and operable in response to some act performed incident to the loading or discharge of passengers on a car at any floor for operating the landing signal at such floor for that car, and means dependent for its operation upon the previous operation of said last-named means for restoring to non-signaling condition the passenger controlled means at such floor if in signal preparing position.

Signed at Hoboken, in the county of Hudson and State of New Jersey, this 13th day of December A. D. 1928.
